United States Patent Office

Des. 211,152
Patented May 28, 1968

211,152

JAR

Brooks D. Fuerst, Toledo, Ohio, assignor to Owens-Illinois, Inc., Toledo, Ohio, a corporation of Ohio

Filed May 12, 1967, Ser. No. 7,091

Term of patent 14 years

(Cl. D9—1)

FIG. 1

The side not shown is the same in appearance as the side shown. The characteristic features of this design reside in the configuration shown in full lines on the drawing.

I claim:

The ornamental design for a jar, substantially as shown and described.
